WALL CONSTRUCTION

Application filed May 8, 1929. Serial No. 361,469.

This invention relates to building construction, and has more particular reference to an improved wall structure and method of erecting the same.

Primarily the invention comprehends a wall structure which includes a plurality of inner and outer wall sections or slabs of a predetermined area or areas arranged in superimposed courses, together with plastic columns formed within the confines of and concealed by the wall sections or slabs.

The invention furthermore contemplates a wall structure in which the wall sections or slabs serve in the capacity of form elements for molding or forming the plastic columns within the confines of the completed wall.

The invention furthermore embodies means, such as undercut recesses formed in the wall sections or slabs, into which extend projecting portions or keys constituting an integral part of the plastic columns, whereby to establish a bond between the columns and wall sections so that the columns strengthen, support and connect the edges of the adjacent inner and outer wall sections or slabs.

The invention furthermore resides in a method of erecting the walls wherein inner and outer wall sections or slabs arranged in courses are spaced apart at the juncture of the adjacent slabs by vertically disposed pairs of spacing strips which combine with said sections or slabs to produce a form into which a plastic or cementitious substance is introduced or poured to form columns within the confines of the wall and concealed thereby.

The method more specifically consists in providing during the pouring step of the columns, keys which interlock in undercut receiving recesses on the confronting inner faces of the slabs, so that the columns when set serve to join the adjacent slabs for retaining them against separation while functioning to unite the inner and outer slabs.

Other objects of the invention reside in the simplicity of construction and mode of erection of the wall, the economy with which the same may be produced and the general efficiency derived therefrom.

With the above recited and other objects

in view, reference is had to the following description and accompanying drawings, in which there is exhibited one example or embodiment of the invention, while the claims define the actual scope of the same. 55

In the drawings:

Figure 1 is a sectional plan view through a wall constructed in accordance with the invention and illustrating the temporary clamping means applied to the wall during 60 the formation of one of the columns, said section being taken approximately on the line indicated at 1-1 in Figure 2.

Figure 2 is a fragmentary side view of the wall. 65

Referring to the drawings by characters of reference, A and B designate respectively the inner and outer wall sections or slabs which are molded, cast or otherwise formed of a cementitious or plastic substance suitably reinforced by the embedded reinforcement C. The outer sections or slabs B have their outer surfaces D suitably inlaid or otherwise treated to simulate stone, brick or any other analogous decorative finish, while 70 the inner sections or slabs A have their outer surfaces E formed to present a finished interior wall. The slabs or sections are of a predetermined area and are designed to be arranged in superimposed courses. In order 80 to provide means for strengthening, supporting and joining the sections or slabs A and B, plastic columns F are formed between the inner and outer sections adjacent the juncture of the end edges thereof. In practice, the sections at a distance appropriately spaced from their end edges are provided with vertical grooves G which receive the opposite edges of partition strips H which serve to properly 85 space apart the inner and outer slabs while combining with the slabs to define a space within which the columns F are formed by the pouring of the cementitious or plastic material thereinto. In order to form a bond for

joining the end edges of adjacent pairs of inner and outer slabs, spacing strips I are employed which are placed at the end edges of the adjacent inner and outer pairs of slabs, which spacing strips are of a thickness to extend partially inward of the thickness of 100

the slabs while leaving a remaining groove which receives a portion of the material indicated as the tongues J. In order to further form a bond against lateral separation of the slabs, dovetail or undercut recesses or grooves 5 K are formed in the confronting inner surfaces of the inner and outer slabs to receive a portion of the plastic material in the nature of interlocking keys L. In order to temporarily clamp the slabs in their properly spaced 10 relation during the pouring operation of the columns F, clamp plates 5 are arranged alongside of the outer surfaces of the inner and outer slabs, as clearly illustrated at the right-hand side of the figures, and said clamping plates are formed with registering apertures 15 6 which coincide with the apertures 7 of the slabs to receive therethrough the bolt shanks 8 having heads 9 at one end and threaded terminals 10 at the opposite end for receiving the nuts 11. After the columns F have been 20 poured and set or hardened, it will be appreciated that the temporary clamping means is removed, as well as the spacing strips I. The apertures 7 of the slabs are then pointed 25 up or filled, as at 12, while the spaces left by the removal of the spacing strips I on the inner surface of the wall are pointed up, as at 13. It is, of course, to be understood that the columns F may be suitably reinforced by the 30 embedded reinforcing elements M, if desired.

The method of erecting a wall consists in arranging in spaced parallel relation a plurality of superimposed courses of inner and outer wall sections or slabs A and B, arranging 35 vertically disposed pairs of transverse partition strips between the inner and outer wall slabs on opposite sides of the juncture of the ends of said slabs and then pouring 40 a plastic substance or cementitious mixture into the space defined between each pair of partition strips and the inner and outer wall slabs to form columns within the confines of the wall structure. The method may further 45 include the steps of installing temporary partition strips between the end edges of the adjacent pairs of slabs, which strips are of a lesser thickness than the slabs so as to provide receiving grooves for a portion of the 50 plastic or cementitious substance forming the column whereby to unite the end edges of the slabs. The method may further include the step of keying the slabs to the column by permitting the plastic substance to enter 55 into and form interlocking keys in undercut recesses or grooves in the confronting inner faces of the slabs.

From the foregoing, it will thus be seen that a wall structure and method of erecting the same has been devised, by virtue of which a wall having completely finished outer and inner surfaces is produced, together with a dead air space therebetween, which wall is properly supported and reinforced by columns concealed within its confines.

What is claimed is:

1. A wall structure including spaced parallel inner and outer precast wall slabs respectively arranged in spaced end to end relation and formed adjacent the inner ends of their confronting faces with vertical grooves extending throughout the height of the slabs, said slabs being further provided with undercut recesses extending vertically throughout the height of the slabs and disposed between the grooves and end edges of said slabs, spaced vertical pairs of partition elements arranged transversely between the inner and outer slabs with the side edges of said elements fitted within the grooves and on opposite sides of the end edges of each adjacent pair of inner and outer slabs and a poured plastic column formed within the confines of the wall structure between the partition elements and slabs after the slabs and partition elements have been erected, to constitute means disposed wholly within the confines of the wall structure for effectually connecting the slabs against relative movement and for reinforcing and supporting the wall structure. 90

2. A method of erecting walls consisting in arranging in spaced parallel and end to end relation a plurality of wall slabs, arranging vertically disposed pairs of transverse partition elements between the inner and outer wall slabs on opposite sides of the juncture of the ends of said slabs, temporarily clamping the wall slabs and partition elements in said relation by exerting external inward pressure thereagainst, and pouring a plastic substance into the space defined between each pair of partition strips and the inner and outer wall slabs, to form columns within the confines of the wall structure for strengthening the same and for joining and supporting the slabs. 105

3. A method of erecting building walls consisting in arranging a plurality of inner and outer wall slabs respectively in end to end relation, arranging transversely therebetween at opposite sides of the juncture of adjacent pairs of slabs vertically disposed partition elements, arranging between the ends edges of adjacent slabs spacing strips of lesser thickness than said slabs with the outer surfaces of the spacing strips flush with the outer surfaces of the slabs, temporarily clamping in place by external inward pressure, the inner and outer slabs and the partition elements and then pouring a plastic substance into the space defined between the partition elements and the wall slabs to form columns within the confines of the wall structure in which a portion of said substance extends into the space formed between the end edges of the slabs to serve as a bond for joining the same. 110

4. A method of erecting building walls consisting in arranging in spaced, parallel and end to end relation precast plastic slabs, ar- 130

ranging vertically disposed pairs of partition elements transversely between the inner and outer walls of the slabs on opposite sides of the juncture of the adjacent ends of the slabs in such a manner as to prevent relative separation of the partition elements with respect to each other, temporarily clamping the wall slabs and partition elements in said relation by exerting external inward pressure thereagainst, pouring a plastic substance into the space defined between each pair of partition elements and the inner and outer wall slabs to form columns within the confines of the wall structure for bonding the slabs together and for reinforcing and supporting the wall structure and then removing the temporary clamping means after the plastic substance forming the columns has set.
